SAFETY MEANS FOR RAILROAD SWITCH STANDS

Clarence Stubblefield, Corsicana, Tex.

Application April 21, 1941, Serial No. 389,659

3 Claims. (Cl. 246—220)

This invention relates to new and useful improvements in railroad switch stands and more particularly to safety means and signal means therefor.

The principal object of the present invention is to provide a lock for railroad switch stands which is associated with a switch and remotely located track signal to the end that should the stand be tampered with to the extent that the switch is opened, even partly, the remote signal 10 will be energized.

Other objects and advantages of the invention will become apparent to the reader of the following specification.

In the drawings:

Figure 1 represents a diagrammatic view showing the electrical connections between the electrical elements involved.

Figure 2 is a fragmentary side elevational view showing a railroad with the switch stand and signal mounted adjacent thereto.

Figure 3 is a top plan view of the structure shown in Figure 2.

Figure 4 is a side elevational view of the switch stand.

Figure 5 is a horizontal enlarged sectional view taken substantially on the line 5—5 of Figure 4.

Figure 6 is a sectional view taken substantially on the line 6—6 of Figure 5.

Figure 7 is a fragmentary detailed sectional view taken substantially on the line 7—7 of Figure 5.

Figure 8 is a fragmentary front elevational view of the signal unit.

Figure 9 is a vertical sectional view through the switch unit taken substantially on the line 9—9 of Figure 8.

Figure 10 is a horizontal sectional view taken substantially on the line 10—10 of Figure 8.

Referring to the drawings wherein like numerals designate like parts it can be seen that numeral 5 generally refers to the improved switch stand located adjacent a railroad switch 6, while numeral 7 generally refers to the remote signal controlled by the improved switch stand 5.

The switch stand consists of a box 8 in which is located suitable mechanism of a conventional nature for actuating the switch 6 through the rotation of a shaft 9.

Uprights 10, converging inwardly, serve to support a platform 11 substantially above the box 8 and upon this platform 11 is horizontally movable a segmental-shaped box 12 having a hinged lid 13 and suitable fastening means 14 therefor. The shaft 9 extends upwardly well above the

platform 11 and is equipped with a target or signal element 15.

An upstanding stop flange 16 is provided on the edge portion of the platform 11 and a second stop flange 17 is provided at a diametrically opposite point. Adjacent the flange 17, the platform 11 is formed with a slot 18 in which a handle 19 is operative. Ninety degrees removed from the slot 18 is a second slot 20 in which the handle 19 is seatable when the box 12 has been rotated ninety degrees.

Upon the bottom of the box 12 is a shed 21 in which a block 22 is slidably disposed. The block 22 has a shank 23 extending therefrom and 15 through an aperture boss 24 in the side wall of the segmental box 12. A knob 25 is provided at the outer end of the shank 23. As is clearly shown in Figure 7, a coiled compression spring 26 is interposed between a bracket 27 on the arcuate wall of the segmental box 12 and the block 22, serving to urge the block to a position in the path of the inner end *a* of the handle 19, it being observed that the handle 19 is pivotally mounted between one side wall of the segmental box 12 20 and an ear 27' rising from the bottom of the box, the end portion *a* operating through a slot 28 in the bottom and one end of the arcuate wall of the segmental box 12.

Journalized through a bearing 28' on the shed 21 is a shaft 29 having a depending finger 30, which is operative through a slot in the top portion of the shed 21 to act as a stop against movement of the block 22 to a position freeing the handle 19, unless the shaft 29 has been rotated.

Numeral 31 denotes a key for engagement with the adjacent end of the shaft 29, which when properly fitted with the shaft 29 permits rotation of the shaft to remove the finger 30 from abutting relation with the slide block 22, to the end that the knob 25 can be grasped and pulled to remove the block 22 from obstructive position with respect to the end portion *a* of the handle 19. Obviously, when the block 22 has been moved to the left in Figure 7, the handle 19 is free so that it can be moved to the horizontal dotted line position shown in Figure 6. Thus the handle 19 is freed from the platform 11 so that the shaft 9 and segmental box 12 can be rotated to abut the stop flange 16 where the handle is dropped to seat in the slot 20.

Brackets 32 extend from one side wall of the segmental box 12 and serve to support a stationary block 33 of insulation and a swingable block 34 of insulation. The block 33 carries a contact 35, while a contact 36 is carried by the block 34.

in opposed relation to the contact 35. The block 34 has a short tail portion 37 depending and between this and the opposed side wall of the segmental box 12 is a compression spring 38 serving to hold the contact 36 normally spaced from the contact 35. A lug 39 rises from the aforementioned shaft 29 and a spring 40 connects this lug 39 with an arm 41 extending from the contact block 34, to the end that when the shaft 29 is rotated to free the block 22 by the action of the key 31, the contact 36 will be brought against the contact 35, so that current will flow from the battery 42 (see Figure 1) along the rail section 43 to a conductor 44 to the contact 36 and the contact 35 to a conductor 45 and from there to the opposed rail section 46, the current then passes by way of a conductor 47 to a motor 48 located in the remote signal unit 1 and to a signal lamp 49 before returning to the battery 42. Deenergization of the unit 1 takes place even before the box 12 is rotated so that if there is anything wrong with the switch 6 and however partly open or split it may be, the signal unit 1 will be energized to warn trainmen.

A contact 50 is carried by the segmental box 12 and protrudes downwardly through a slot 51' in the bottom of the box 12. On the platform 11 is a contact 51 against which the contact 50 will engage when the box has been brought to abutting position against the stop flange 16. Due now to the fact that the contacts 50 and 51 are engaged, the key 31 can be removed, leaving the block 22 in an obstructing position with respect to the arm 19 and, of course, as the key 31 and shaft 29 are rotated, the lug 39 will move to a position releasing the spring 40 to the end that the contacts 35 and 36 will separate. Current will now pass by way of the switch 50, 51 instead of 35, 36 (see Figure 1). To maintain the parts in locked position shown in Figure 1, the shaft 29 has a lug 52 between which and an ear 53 on one side wall of the box 12 a coiled tension spring 54 is interposed.

The remote signal means is of simple construction, consisting of a base box 55 from which rises a hollow post 56 having a hollow head 57 from which projects a shaft 58. Numeral 59 denotes a semaphore carried by the shaft 58 and this has a plate structure 60 provided with a green window 61 and a red window 62, one or the other of which is capable of being positioned in front of a bull's eye 63 in the front wall of the hollow head 57, the bull's eye 63 being located in front of the bulb 49 suitably mounted within the hollow head structure 57.

The shaft 58 has an arm 64 from which extends a cable 65. This cable 65 extends downwardly to a drum 66 driven by the motor 48.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. In a switch stand for operating a railroad switch and closing a remote signal circuit, a peripherally notched disc-like table, a segmental box operatively connected to the switch and rotatable on said table about the center thereof into different set positions to open and close the switch, a switch lever on said box for rotating

the same and swingable thereon into and out of said notches to establish the set positions of the box, manipulative means in said box normally blocking the swinging of said lever out of either notch and including an operating shank extending out of the box, a lock in said box for retaining said means in normal blocking position and key operated to unlock the same, a pair of normally open contacts adapted to close said circuit and operative to closing position under unlocking of said lock, and a pair of contacts on said table and box, respectively, open in one set position of the box and adapted to be engaged to close said circuit under rotation of said box to another set position to thereby maintain said circuit closed when the lock is locked and the first-mentioned pair of contacts thereby opened.

2. In a switch stand for operating a railroad switch and closing a remote signal circuit, a peripherally notched disc-like table, a segmental box operatively connected to the switch and rotatable on said table about the center thereof into different set positions to open and close the switch, a switch lever on said box for rotating the same and swingable thereon into and out of said notches to establish the set positions of the box, manipulative means in said box normally blocking the swinging of said lever out of either notch and including an operating shank extending out of the box, a lock in said box for retaining said means in normal blocking position and key operated to unlock the same, a pair of normally open contacts adapted to close said circuit and operative to closing position under unlocking of said box, and a pair of contacts on said table and box, respectively, open in one set position of the box and adapted to be engaged to close said circuit under rotation of said box to another set position to thereby maintain said circuit closed when the lock is locked and the first-mentioned pair of contacts thereby opened, said means comprising a slide block spring tensioned toward normal position.

3. In a switch stand for operating a railroad switch and closing a remote signal circuit, a peripherally notched disc-like table, a segmental box operatively connected to the switch and rotatable on said table about the center thereof into different set positions to open and close the switch, a switch lever on said box for rotating the same and swingable thereon into and out of said notches to establish the set positions of the box, manipulative means in said box normally blocking the swinging of said lever out of either notch and including an operating shank extending out of the box, a lock in said box for retaining said means in normal blocking position and key operated to unlock the same, a pair of normally open contacts adapted to close said circuit and operative to closing position under unlocking of said lock, and a pair of contacts on said table and box, respectively, open in one set position of the box and adapted to be engaged to close said circuit under rotation of said box to another set position to thereby maintain said circuit closed when the lock is locked and the first-mentioned pair of contacts thereby opened, said means comprising a slide block spring tensioned toward normal position, said lock including a spring tensioned rotary shaft, and a finger on said shaft for obstructing movement of said block.
